UNITED STATES PATENT OFFICE.

JOSEPH MORTZ, OF CORRY, PENNSYLVANIA, ASSIGNOR OF ONE-HALF TO
FRANK S. BARNEY, OF SAME PLACE.

CARTRIDGE-LOADING MACHINE.

SPECIFICATION forming part of Letters Patent No. 389,936, dated September 25, 1888.

Application filed May 21, 1888. Serial No. 274,569. (No model.)

To all whom it may concern:

Be it known that I, JOSEPH MORTZ, a citizen of the United States, residing at Corry, in the county of Erie and State of Pennsylvania, have 5 invented certain new and useful Improvements in Cartridge-Loading Machines; and I do hereby declare the following to be a full, clear, and exact description of the invention, such as will enable others skilled in the art to which it applies to make and use the same, reference being had to the accompanying drawings, and to the letters of reference marked thereon, forming part of this specification.

My invention consists in the improvements 15 in cartridge-loading machines hereinafter set forth and explained, and illustrated in the accompanying drawings, in which—

Figure 1 is a rear view, in elevation, of my improved cartridge-loading machine. Fig. 2 20 is a vertical central section of same on the line x in Fig. 1, looking in the direction of the arrow.

Like letters refer to like parts in both of the figures.

25 In the construction of my improved cartridge-loading machine shown, A is the powder-receptacle, B the shot-receptacle, and C the wad-receptacle, of my machine. The receptacles A and B, I make, preferably, of cylinders of glass secured between heads a and a' and b and b' , the upper heads, a' and b' , having openings therein, provided with screw-caps D and E, and the lower heads, a and b , being made hopper-shaped, with passages d e (the 30 parts being broken away in Fig. 1 to show said passages) therewith, adapted to communicate with the rotating powder and shot measures F and G when in proper position therefor, as illustrated by the position of the powder-measure F in Fig. 1, or closed by the circular valve-fans f and g thereon, as illustrated by the position of the shot-measure G in Fig. 1. These rotating measures F and G, being 35 also adapted to communicate in like manner with and empty their contents into the inclined passages H and I, which open into the vertical tube J, so that the powder and shot measures F and G, being alternately filled from the powder and shot receptacles A and 40 B, may be rotated, as hereinafter described,

so as to alternately discharge their contents into the vertical tube J, whence they pass down into a cartridge-shell (not shown) in the shell-holder K.

The rotating measures F and G are each 55 provided with axes h and i , mounted in the frame of the machine, and to these axes crank-arms j k are secured, which are connected together by means of a bar, L, secured thereto by pintles l , the crank-arms j k being so secured to the axes h i that the measures F and G will occupy positions relative to each other, as shown in Fig. 1—that is to say, when one is being filled the other is discharging its contents. To the axis h , I also secure a crank- 60 arm, M, to which is pivoted a connecting-bar, m , the end of which is pivoted to the bell-crank lever N, pivoted at n to a movable support, O, pivoted to the frame at O', the arm n' of the bell-crank lever N serving as the handle for 65 operating the rotating measures F and G by means of the communications described. On each of the measures F and G the semicircular plates or valve-faces f and g rotate in circular valve-seats f' and g' at the lower ends of the 70 passages d and e and serve to close and keep the same closed until the measures F and G are in proper position to be filled, the circular seats f' and g' also serving to prevent the 75 contents of the measures F and G from being spilled until they respectively arrive at the proper positions to discharge their contents into the passages H and I. The measures F and G are also provided with movable bottoms d' and e' , which are adapted to be adjusted so as to vary the capacity of the 80 measures F and G, as desired.

To the frame of the machine, in the rear of and between the powder and shot receptacles A and B, I secure the vertical tube C, which 90 is provided at its upper end with a hopper, C', adapted to receive and retain a supply of wads for use in operating the machine. The lower end, c , of the tube C extends down to and opens upon a transverse sliding plate, P, which 95 slides freely back and forth in guides P' in the machine-frame, the plate P being so located as to operate directly over the upper end of the vertical tube J, hereinbefore described.

In the plate P, I make a slot, p , so that when 100

the slot p is moved under the lower end, e , of the wad-tube C one of the wads drops by gravity into the slot p , where it is ready to be drawn out over the upper end of the tube J , so as to be acted upon by the plunger Q , as hereinbefore described.

The plunger Q is mounted in a bearing, Q' , in the frame, directly over the upper end of the tube J , in such position that it will readily pass down through the slot p in the plate P , and through the vertical tube J into the cartridge-shell holder K , so as to drive a wad down into a shell (not shown) held in the cartridge-shell holder K and supported vertically by the movable anvil K' .

On the upper end of the plunger Q there is a laterally-projecting arm, R , provided on its outer end with a bearing, R' , in which the operating-lever S is pivoted, one end, S' , of the lever S being pivoted at u to the upright arm O and the other end thereof being provided with an operating-handle, S'' .

Through the arm R on the plunger Q a vertical rod, T , passes, sliding freely through an opening, r , (shown in dotted lines,) therein, this rod extending from the top of the sliding plate P to some distance above the arm R , where it is provided with a head, T' . This rod T also passes near its lower end loosely through an opening, t , in the machine-frame, and is supported laterally thereby, so that it will slide freely up and down in its supports. In front of the rod T , where it passes through the opening t in the frame, is an outwardly-extending ear or lug, U , in which is pivoted a bell-crank lever, U' , the short arm u of which extends inwardly, where it engages with a notch, u' , in the lower end of the vertical rod T , and also with the lower end of the plunger Q , during its downward traverse to the top of the plate P , and the long arm V thereof extends downward and engages with a slot, v , in the front end of the sliding plate P , so that the movement of the bell-crank lever U' actuates the sliding plate P forward and back, as hereinbefore set forth.

The cartridge-shell holder K is secured in a clamp, K' , pivoted on a trunnion, l , passing through the frame, so that it can be freely rotated thereon, a stop, 2 , extending downward from one side of the vertical tube J , engaging therewith when brought to a vertical position, as illustrated in Fig. 1.

Directly under the lower end of the cartridge-shell holder K is the anvil K' , upon which the head of the cartridge rests when being loaded. This anvil K' is movable and is supported by a bracket, 3 , held in place by an adjustable screw, 4 , by means whereof it can be raised or lowered, as desired. The central portion of the anvil K' is provided with a slot, 5 , (shown in dotted lines,) whereby it can be moved forward and back, the rear end passing under a hook, 6 , on the support 3 , so that when in place it is firmly supported; but when pulled forward by means of the handle 7 thereof it

will become disengaged from the hook 6 and fall down in front, so that the cartridge-shell can be easily withdrawn from the holder K , or so that the holder K , with the loaded cartridge, can be rotated so as to occupy a horizontal position between the parts 8 and 9 of the crimping, these parts of the crimping being mounted in bearings 10 and 11 in the sides of the frame in such position that the cartridge-holder K when in a horizontal position is in the proper position to present the cartridge to the crimping. The crimping is of usual and ordinary construction, the rotating head 9 being operated by turning the crank 12 , the wad being meanwhile held in place by the plunger 13 , the cartridge-head support 8 being moved forward and back by means of a hand bell-crank lever, 15 , an arm, 16 , of which operates in a slot in the outer end of the support 8 , and the other arm being provided with a handle, 17 , for operating the same. The lower part of the frame is provided with screw-clamping mechanism 18 and 19 , by means whereof the machine may be secured in an upright position to a counter, table, or other suitable support.

In operation a cartridge-shell is placed in the cartridge-holder K and the anvil K' raised into position and secured so as to support the head of the cartridge-shell with its open end directly in contact and line with the lower end of the vertical tube J . The operator then raises the handle u' , which discharges the contents of the powder-measure F into the shell through the passage H and tube J . The operator then raises the handle S'' , which raises the plunger Q , and the rod T , which operates the bell-crank lever U , and slides the plate P back until the slot p is directly under the lower end of the wad-tube C , when a wad drops by gravity therein. At this time the end of the arm u of the bell-crank lever U' is under the lower end of the plunger Q . The lever S is then moved downward, when the lower end of the plunger in its downward traverse operates on the arm u of the bell-crank lever U' to draw the plate P forward, so that when the lower end of the plunger Q has reached the plate P the slot p , with a wad therein, is directly in line with the lower end of the plunger Q , which in its continued downward traverse forces the wad down through the tube J into the shell below. The movement of the handle S'' being then reversed, the plunger is withdrawn and the plate P again forced back. The operator then reverses the movement of the handle u' , which returns the measure F to the position to be filled, while at the same time it discharges the shot-measure G through the passage I and tube J into the shell, and a downward movement of the handle S'' drives another wad into the shell on the top of the shot, as hereinbefore described, thereby completing the loading of the shell. The anvil K' , being then drawn forward, drops down out of the way. The shell-holder K is then rotated, so as

to bring the shell between the parts 8 and 9 of the crimper, where it is crimped. The loaded shell is then removed from the holder K.

Having thus fully described my invention so as to enable others to construct and operate the same, what I claim as new, and desire to secure by Letters Patent of the United States, is—

1. The combination, in a cartridge-loading machine, of rotating measures having circular valve-faces thereon, with cranks on said rotating measures, a connecting-rod connecting said cranks together, and a lever connected to one of said cranks, so that said measures may be simultaneously rotated thereby, substantially as and for the purpose set forth.

2. The combination, in a cartridge-loading machine, of a powder-receptacle and a rotating measure connecting with the bottom of the same, and a shot-receptacle and a rotating measure communicating with the bottom of the same, with a crank secured to each of said measures at such angle that a connecting-rod between said cranks will simultaneously rotate said measures, so that one measure will be filled while the other is being discharged, and a common conduit below said measures, into which both measures alternately discharge their contents, substantially as and for the purpose set forth.

3. The combination, in a cartridge-loading machine, of powder and shot receptacles having hopper shaped bottoms opening through circular valve-seats, with rotating cut-off valves having cranks thereon and a connecting-rod between said cranks, said valves fitting and rotating in said circular valve-seats, and powder and shot measures in said rotating valves, having movable bottoms, whereby the capacity of the measures may be altered and adjusted, substantially as and for the purpose set forth.

4. The combination, in a cartridge-loading machine, of a vertical wad-tube located in the rear of the plunger and adapted to operate as a wad-supply magazine, and a horizontally-sliding plate having an oblong slot therein moving back and forth under the lower end of the wad tube and plunger, with a bell-crank lever pivoted in the machine-frame, so that one arm thereof engages with the end of said sliding plate and the other with the lower end of the plunger, and with a vertically-moving rod thereon, whereby the said plate is moved back and forth by the positive action of the parts, substantially as and for the purpose set forth.

5. The combination, in a cartridge-loading machine, of an upright loading-tube and shell-holder and a sliding plate for conveying wads from a wad-holding tube to and over the loading-tube, with bell-crank-lever mechanism pivoted to the frame and engaging with the end of said plate and with the lower end of the plunger for moving the plate forward, and a vertical rod operated by the plunger and en-

gaging with said bell-crank lever for moving the plate back, substantially as and for the purpose set forth.

6. The combination, in a cartridge-loading machine, of a powder-receptacle and shot-receptacle, and measuring mechanism rotating on horizontal axes connecting said receptacles with an upright tube, with a rotating shell-holder under said tube, a movable anvil under said shell-holder, and crimping mechanism in the line of rotation of said cartridge-shell holder, substantially as and for the purpose set forth.

7. The combination, in a cartridge-loading machine, of powder and shot receptacles and a wad-receptacle, valve-measures rotating on horizontal axes adapted to convey the contents of the powder and shot receptacles into an upright loading-tube, and lever mechanism for simultaneously operating said valve-measures, with a plunger operating down through the loading-tube, a sliding slotted plate operating under the end of the wad-tube and plunger for moving wads over the loading-tube, bell-crank-lever mechanism connecting said sliding plate with the plunger, and lever mechanism for operating the plunger, substantially as and for the purpose set forth.

8. The combination, in a cartridge-loading machine, of the powder and shot measures F and G, having adjustable bottoms d' and e' therein, and circular valve-faces f and g thereon, adapted to fit in the circular valve-seats f' and g', openings d and e in the powder and shot receptacles for filling said measures, and pipes H and I, through which said measures may be emptied, with cranks j and k on said valves, and a connecting-rod, L, so connecting said cranks j and k that said measures may be simultaneously rotated, so as to alternately fill one measure while the other is being discharged, substantially as and for the purpose set forth.

9. The combination, in a cartridge-loading machine, of a vertical powder-receptacle, A, a vertical shot-receptacle, B, a horizontal rotating powder-measure, F, communicating with said powder-receptacle, and having a circular valve-face, f, thereon, operating in a circular valve-seat, f', a horizontally-rotating shot-measure, G, communicating with said shot-receptacle, and having a circular valve-face g thereon, operating in a circular valve-seat, g', cranks j and k on said rotating measures, connected together by a connecting-rod, L, so as to operate in unison, a vertical loading-tube, J, diagonal passages between said rotating measures and said tube, and lever mechanism M m N O, for operating said rotating valves, with a vertical wad-receptacle above the loading-tube J, a horizontally-sliding slotted plate, P, operating under the lower end of the wad-receptacle and over the upper end of the loading-tube, a vertical plunger, Q, adapted to operate in the loading-tube, and a bell-crank lever, U', connecting the sliding

plate P with the plunger Q, and the levers S O, adapted to operate the plunger mechanism, substantially as and for the purpose set forth.

10. The combination, in a cartridge-loading machine, of the sliding slotted plate P, with the bell-crank lever U, the plunger Q, operating on said bell-crank lever to draw the plate P forward, and the rod T, actuated by the plunger and operating on said bell-crank lever

to move the plate back, substantially as and for the purpose set forth.

In testimony whereof I affix my signature in presence of two witnesses.

JOSEPH MORTZ.
